UNITED STATES PATENT OFFICE.

FREDERICK W. HECKLER, OF DARBY, PENNSYLVANIA.

HOLDER FOR VALVES WHILE BEING GROUNDED.

1,391,733.

Specification of Letters Patent. Patented Sept. 27, 1921.

Application filed July 13, 1920. Serial No. 395,896.

To all whom it may concern:

Be it known that I, FREDERICK W. HECKLER, a citizen of the United States, residing at Darby, in the county of Delaware, State 5 of Pennsylvania, have invented a new and useful Holder for Valves While Being Ground, of which the following is a specification.

My invention consists of a device for 10 holding a valve while being ground, the same embodying jaws which may be centered against the interior wall of the collar of the valve and avoiding marring or grooving of the exterior of the latter by such 15 jaws, means for tightening said jaws on the valve and retaining them firmly thereon and on a valve seat, means for rotating the device and other details are provided whereby the grinding action of both the valve and 20 its seat may be accomplished in a convenient, effective, steady and true manner as will be hereinafter set forth.

The invention is satisfactorily illustrated in the accompanying drawing, but the important instrumentalities thereof may be varied, and so it is to be understood that the invention is not limited to the specific details shown and described, as long as they are within the spirit or scope of the claims.

30 Figure 1 represents a side elevation of a holder for a valve while being ground, the same embodying my invention.

Fig. 2 represents a partial side elevation and partial vertical section thereof.

35 Fig. 3 represents a view similar to Fig. 2 showing certain parts in different positions from those in Fig. 2.

Fig. 4 represents a top or plan view of the device on an enlarged scale.

40 Fig. 5 represents a partial side elevation of another embodiment of the invention.

Similar numerals of reference indicate corresponding parts in the figures.

Referring to the drawings.

45 1 designates a tubular head or stock on whose lower portion are pivoted the jaws 2 which depend therefrom and are of elbow form, the lower limbs 3 whereof are adapted to enter the collar 4 of the valve 5 to be 50 ground, the upper limbs 6 whereof are adapted to project inwardly toward each other beneath the head 1.

The bore of said head is threaded and has 55 engaging with it the wide threaded portion 7 of the movable spindle 8, above which portion is the threaded portion 9 thereof, it

being noticed that said portions are of different diameters and have their threads respectively right and left pitched, it being noticed also that the lower portion of the 60 spindle enters the head 1 and its bottom end 10 which is about the bottom of the head is adapted to engage the upper limbs 6 of the jaws 2.

The narrow threaded portion 9 of the 65 spindle does not engage with the threads of the bore of the spindle and so is adapted to slide freely thereon, but when the spindle is lowered when rotated the threaded portion 7 thereof then engaging the threaded bore 70 of the head, the lower end of the spindle is adapted to bear downwardly upon the limbs of the jaws 2 whereby the lower limbs 3 of the latter are spread apart, this being occasioned when the jaws are entered in the collar 4 of the valve.

In order to retain the jaws in normal or closed condition as shown in Fig. 2 there are connected with the side of the head the springs 11 which depend therefrom and engage the upper portions of the jaws 2 below the axes 12 thereof so as to force said jaws inwardly whereby the limbs 3 may readily enter the collar 4 preparatory to tightening them therein.

On the narrow threaded portion 9 of the spindle 8 above the head 1 is the nut 13 which is adapted to be jammed against the top of said head so that when the jaws are adjusted in the collar 4 and tightened there- 90 against said spindle and consequently the jaws are prevented from movement and disengaging the jaws from the collar.

The spindle 8 has its upper portion passing freely through the cross bar 14 on the valve casing 15, on the lower portion 16 of which latter is mounted the valve seat 17 on which the conical surface of the valve 5 is adapted to be placed and so be ground by the same the seat being also ground.

On the portion of the spindle 8 below the cross bar 14 is the coil spring 18 which is adapted to bear against the underside of said cross bar and the collar 19 which is secured to said spindle by the screw 20 where- 105 by the spindle and connected parts are adapted to be lowered thus forcing down the jaws 3 against the base of the collar 4 of the valve, and so assists in retaining said jaws in position on said base while also forcing the valve against the grinder so as to remain properly seated thereon.

The spindle has thereon on its upper end the crank handle 21 for rotating the same and so imparting by the intermediate members rotation to the valve 5 and cause the 5 grinding of the latter on the seat 17 and vice versa.

The cross bar 14 is connected with the adjacent portions of the casing 15 by means of the bolts 22 which are passed through 10 either of the slots 23 in said cross bar into the frame 15, it being removable from said frame, so convenient in manipulation of the device in applying and removing the valve to and from the same.

15 The operation is as follows:—

The valve is presented to the jaws so that the latter enter the same and rest on the base of collar, and the valve is placed on the valve seat 17, said jaws being in closed condition.

20 The spindle is then rotated whereby it depresses the upper limbs 6 of the jaws when the lower limbs of the jaws are forced out and so tightened against the inner face of the collar, the valve thus being firmly connected 25 with the jaws.

30 The jam nut 13 is also rotated on the spindle so as to tighten against the head, and so the spindle and head are clamped together as one. The spindle is then rotated whereby it communicates similar motions to the head and jaws and consequently to the valve, and so the latter is rotated on the seat 17 and thus both are effectively and uniformly ground, the valve being furthermore 35 resiliently pressed down on the seat as grinding continues due to the action of the spring 18.

40 When the work is accomplished, the nut 13 may be unscrewed when the spindle may be rotated on reverse direction and so relieve the jaws of their holding action on the valve when the valve may be manipulated to be removed from the jaws and consequently from the grinding member, or the cross bar 45 14 may be disconnected from the casing 15 and the entire device with the valve removed from the seat when the spindle may be manipulated to release the valve from the jaws.

50 In Fig. 3 I show the jaws 2 opened or spread to a great extent showing that the device is capable of grinding valves of vastly increased diameter over that shown in Fig. 1.

55 In Fig. 5, I show certain parts of the device in position adapting the device for holding a valve while being ground in a position

reversed to that shown in Fig. 1, that is the valve grinding mechanism and jaws with the connections of the latter will be above the cross bar 14 of the frame, all other parts being 60 assembled in harmony with the same.

Having thus described my invention what I claim as new and desire to secure by Letters Patent, is:—

1. In a valve grinding device, a tubular head, a threaded spindle having a threaded portion engaging the threaded bore of the head and a narrow threaded portion which is free from engagement with said threaded bore of the head, elbow-shaped jaws pivotally mounted on said head and having in-turned limbs at top extending in the path of the spindle, jamming means on the narrowed threaded portion of the spindle adapted to bear against said head, and means resiliently pressing on the spindle to force the valve to its seat while being ground. 65 70 75

2. In a valve grinding device, a tubular head, a threaded spindle having a threaded portion engaging the threaded bore of the head and a narrow threaded portion which is free from engagement with said threaded bore of the head, elbow-shaped jaws pivotally mounted on said head and having at top in-turned limbs extending in the path of the spindle, jamming means on the narrowed threaded portion of the spindle adapted to bear against said head, means resiliently pressing on the spindle to force the valve to its seat while being ground, and springs on the head bearing inwardly against said jaws 80 85 90 adjacent their pivots to close said jaws.

3. In a valve grinding device, a tubular head, a threaded spindle therein, jaws mounted pivotally on said head and depending therefrom, said jaws having at the top 95 in-turned limbs extending in the path of the spindle in descending adapted to lower said limbs and spread said jaws into a collar of a valve, a cross bar connectible with a valve having said spindle pass freely therethrough, a movable collar on said spindle, and means for holding the former in adjusted position, and a resilient member intermediate of said collar and cross bar adapted to force down 100 said spindle and consequently said jaws and press the valve upon its seat.

FREDERICK W. HECKLER.
